UNITED STATES PATENT OFFICE

HARLEY T. WHEELER, OF DALLAS, TEXAS, ASSIGNOR TO BETH H. WHEELER, OF DALLAS, TEXAS

NONREVERSIBLE PUMP

Application filed September 14, 1926. Serial No. 135,384.

This invention relates to vacuum pumps and it has particular reference to certain new and useful improvements in liquid beverage pumps adapted especially for use in soda dispensing fountains, and its principal object 5 resides in its capability of predetermining the quantity of liquid dispensed at each operation, thus effecting a considerable saving in the commodity by the apparent uniformity of discharge.

Another object of the invention resides in the novelty of structure, particularly the pressure equalizing means controlling the piston, and further, the means for restraining the piston against reversal movement in incomplete stages of operation or premature suspension of liquid flow.

Still another and important object of the invention resides in the peculiar form of the discharge orifice of the spout, so constructed as to obviate leakage while not in use, and as a measure against waste.

With these objects and advantages in view, other objects as well as certain features of 25 construction and arrangement of parts will become apparent as the description proceeds taken in connection with the accompanying drawings, wherein:

Figure 1 represents a rear elevational view 30 of a pump constructed according to the present invention.

Figure 2 is a side view thereof, and

Figure 3 is an elevational view in vertical cross-section illustrating the fluid passages 35 and control valves.

Continuing more in detail with the drawings, it will be observed in Figures 1 and 2 that a frame 1 is provided of such form as to rigidly support the parts, consisting principally of the cylinder 2, piston 3 and ratch bar 4. As apparent, the frame is readily removable for adjusting, repairing or cleaning the parts.

The pump is so constructed as to be operative in the conventional syrup receptacle forming part of the equipment of standard soda fountains without alteration in any respect, and may be adjusted, as will presently become apparent, to dispense any quantity of liquid desired in uniform measures. The top

5 is arranged to conformably fit into the receptacle to provide a desirably tight joint, but may be lifted out, in cases where the small receptacle is used, to refill; however, in some cases, it is desirable to maintain a supply of 55 liquid beverage in a larger container behind the fountain, and in this case, the fluid pipe 6, in which is contained a check valve 7 is directed into the container which serves equally as well as in the former case.

The cylinder 2, while it may be of any capacity, is ordinarily constructed to contain an ounce of syrup as a beverage ingredient, and has operating therein the piston head 8, as in Figure 3, situated upon the piston 3, 60 which latter extends upwardly, through a sleeve 9, passing through the top 5 and both are connected to a hand lever 10, pivoted at a 65 at a spaced distance from the piston. The sleeve 9 is surrounded by a bushing 11 mounted in the top 5. A cross head 12 is carried by the lower end of the sleeve 9 and is held thereon by a set screw 13, as apparent in Figure 1, and interposed between this cross head and the cylinder 2 is a resistance element composed of reversely wound expansion springs 14. This particular feature is materially instrumental in bringing about equalization of 70 pressure imparted to the piston in its travel both downward and upward.

A vertical fluid passage 15 is situated in vertical parallel relationship with the piston 3, and has screwed thereon a dispensing spout 16, to which reference will be later and more fully made. Within this passage 15 reposes a 75 check valve 17 near the discharge end, and at the bottom thereof a communicating passage-way 18 enters the cylinder 2 at a level with the bottom of the passage 15.

Referring now especially to the means for 80 restraining the piston against reverse movement in incomplete stages of operation; attention is directed particularly to Figures 1 and 2, showing the vertical ratch bar 4, previously referred to, situated in the frame 85 in parallel relationship also with the piston 3, and rigidly mounted upon the cross head 12 is a member 20, to which is pivotally connected a double acting detent 21, operatively 90 engaging the notches in the bar 4 at its either 95 top 100

end, depending upon the direction of travel of the piston 3. In order to urge the opposite ends of the detent into engagement with the notches of the bar 4, a tension spring 22 is supplied, which has one end connected to a rearwardly extending arm 23 integral with the detent 21, while its opposite end is connected to the member 20. The action of the spring obviously holds the arm 23 off center, hence holding one or the other of the operative points of the detent in engagement. Reversibility of the detent is accomplished by spaced stops 24, adjustable upon the bar 4 by set screws 25, provided with opposed pins 26, which latter are engaged by the detent, thus throwing the arm 23 under tension of spring 22 to a reverse position, the detent resisting the action of the springs 14 upon downward movement of the piston.

20 In operation, a slight adjustment may be made to vary the discharge quantity to any amount less than the capacity of the cylinder 2 by relative movement of the stops 24 upon the ratch bar 4. Should it be desired to increase the quantity of discharge, it is then necessary to substitute a larger cylinder.

Assuming that the predetermined capacity of the cylinder 2 is one ounce; a like quantity may be contained within the passages 18 and 15. Pressure upon the operating handle 10 will depress the piston 3, hence the piston head 8, such action forcing that liquid contained within the cylinder 2, through the by-pass 18, thus raising the column of liquid contained within the passage 15 through the check valve 17 and discharging the same. It will be understood from the foregoing description that during downward movement of the piston 3, it is not possible to raise the same until the cylinder 2 is exhausted of its contents, thus maintaining at all times a predetermined quantity of liquid within the passage 15. This action applies likewise upon upward movement of the piston rod 3.

45 When the piston 3 reaches the extreme ejecting position, the lower stop pin 26 contacts with the arm 23 of the detent 21, reversing the latter and permitting the piston then to rise by the action of the springs 14.

50 Partial vacuum created by the upward movement of the piston head 8 recharges the cylinder 2 preparatory to further operation.

The parts subject to frictional wear, such as the piston rod 3, and detent 21 may be readily lubricated through tubes 27, communicating with an oil hole accessible at the top of the pump.

Manifestly, the construction illustrated and described is capable of considerable variation, and such variation as is within the scope of the appended claims is considered within the spirit of the invention.

I claim:—

1. In a pump, a cylinder having a piston and piston rod therein, a spring tensioned

sleeve on the upper end of the piston rod, a cross head carried by the lower end of the sleeve, a member rigidly carried by the cross head, a double acting detent pivoted to said member, a stationary rack bar, engageable with said detent, a rearwardly extending arm 70 on the detent, a coil spring connected at one end to said arm and at its opposite end to said member, stops on the rack bar engageable with the respective opposite ends of the 75 detent thereby to reverse the latter, the end of said spring which is connected to said arm of the detent and said arm being movable on opposite sides of the detent pivot thereby to hold the detent in either of its two 80 positions, and means to actuate the sleeve.

2. In a pump, a cylinder having a piston and piston rod therein, a double acting detent, means to pivotally connect said detent to the rod for movement therewith, a rack 85 bar, stops on the rack bar engageable with the respective opposite ends of the detent thereby to reverse the latter, means to actuate the rod, an arm carried by the detent, a member having connection with the piston rod, and a coil spring connected at one end to the member and at its opposite end to the arm, said opposite end of the spring being movable on opposite sides of the pivot of the 90 detent thereby to hold the detent in either 95 of its two positions.

In testimony whereof I affix my signature.

HARLEY T. WHEELER.
